(57) **CLAIM**

The ornamental design for a light switch cover, as shown and described.

DESCRIPTION

FIG. 1 is a top plan view of first embodiment of a light switch cover showing our new design;

FIG. 2 is a front view thereof;

FIG. 3 is a right-side view thereof;

FIG. 4 is a left-side view thereof;

FIG. 5 is a rear view thereof;

FIG. 6 is a bottom plan view thereof;

FIG. 7 is a cross sectional view thereof taken along line 7-7 of FIG. 2;

FIG. 8 is a top front perspective view thereof;

FIG. 9 is an exploded bottom front perspective view thereof;

FIG. 10 is a top plan view of a second embodiment of a light switch cover showing our new design;

FIG. 11 is a front view thereof;

FIG. 12 is a right-side view thereof;

FIG. 13 is a left-side view thereof;

FIG. 14 is a rear view thereof;

FIG. 15 is a bottom plan view thereof;

FIG. 16 is a cross sectional view thereof taken along line 16-16 of FIG. 11;

FIG. 17 is a top front perspective view thereof; and,

FIG. 18 is an exploded bottom front perspective view thereof.
